UNITED STATES PATENT OFFICE

CHARLES C. SUNDERLAND, OF NEW BRUNSWICK, NEW JERSEY, ASSIGNOR TO JOHN A. ROEBLING'S SONS COMPANY, OF TRENTON, NEW JERSEY, A CORPORATION OF NEW JERSEY

CABLE SPINNING APPARATUS

Application filed December 10, 1930. Serial No. 501,311.

This invention relates to spinning wheel devices such as used in spinning parallel bridge cables, the object of the invention being to provide a more efficient spinning wheel 5 mounting which shall avoid the difficulties experienced with previous spinning wheel devices, especially in passing obstacles or turning around guiding sheaves, and by which a higher spinning speed is made practical.

The spinning wheel mounting in general use heretofore consists of two arms projecting sidewise from the traction rope by which they are driven and to which they are clamped, these arms carrying bars forming a V, with its base at the traction rope, from the angle of which projects sidewise a stud upon which the spinning wheel is mounted to rotate freely in line with the traction rope. This construction results in a sidewise strain upon the spinning device and slow speed is necessary in passing traction rope supports or turning curves at the ends of the run, resulting in a considerable reduction of the spinning speed.

In accordance with the present invention, the spinning frame on which the spinning wheel is mounted, is carried by supports extending downward in line with the traction rope and mounted thereon to swing sidewise freely while driven thereby, and the spinning wheel frame is mounted on its swinging support so as to move vertically to accommodate itself to bends of the traction rope, especially in passing support-sheaves through the span or at the end of the spinning run. With this construction, the guide sheaves for the traction rope are arranged in pairs on opposite sides of the traction rope and inclined outward and downward from the under side of the traction rope, so as to provide space for the spinning wheel support to run between them with the traction rope. This construction, also, enables two spinning wheels to be mounted on a single frame for operation.

by the traction rope, thus practically doubling the spinning capacity.

For a full understanding of the invention, a detailed description of a construction of the preferred form embodying all the features 50 of the invention, will now be given in connection with the accompanying drawings forming a part of this specification and the features forming the invention then specifically pointed out in the claims.

In the drawings:—

Figure 1 is a side view of the spinning wheel device in place on the traction rope, in the form suitable for use with a single spinning wheel;

Figure 2 is a cross section on the line 2 of Figure 1, looking in the direction of the arrow;

Figure 3 shows a modification with two spinning wheels, this view being an end elevation looking to the left as in Figure 1;

Figure 4 is a detail cross section on the line 4 of Figure 1.

Referring now especially to Figures 1, 2 and 4, A is the spinning wheel over which the strand loop passes for spinning the cable, as usual in such operations, B the spinning wheel frame in which the spinning wheel A is mounted, and C the end supports and D the intermediate support by which the wheel frame B is swung on the moving traction rope E. The frame B is a rigid frame formed in any suitable manner, being shown as a skeleton frame formed of angle bars to secure the desired strength and rigidity, and at the bottom of this frame the spinning wheel A is mounted to rotate freely on a stud 10 projecting sidewise from the frame B. The frame B is suspended by links 11 from the two end supports C, and has a pin and vertical slot connection 12 with the center support D, so that, by the swinging of the links 11 and its vertical movement on the pin and slot connection 12, the frame B accommodates itself to the vertical curving of the traction rope E.

The end supports C and center support D are swung on the traction rope E by arms 13, which are formed at the end with split sleeves 3 so as to be readily applied to and removed from the traction rope E. Similar sleeves 14, shown in Figure 4, are clamped on the traction rope at such intervals as to permit the curving of the traction rope E while at the same time assuring the movement of the spinning wheel frame with the traction rope, and the spaces between the clamped sleeves 14 and the arms 13 and end sleeves 15 on the traction rope E preferably are filled by split sleeves 16, mounted loosely on the rope, thus permitting the curving of the traction rope while holding the supports C, D in position. The end sleeves 15 are preferably of rubber or other elastic material and tapered away from the spinning wheel frame as shown, so as to readily enter the space between guide pulleys and prevent shock. The halves of the split sleeves are held together by pins 4, as shown in Figure 4 and all the sleeves may be of the same construction except that sleeves 14 are formed to lock on the traction rope and the other sleeves are free to turn and slide on the rope. The end supports C are provided with a series of holes 1 and the top bar of the spinning wheel frame B is provided with a plurality of holes 1' to receive the pins 2 by which the links 11 are mounted in the frame B and supports C, so that the position of these links 11 connecting the frame B and supports C and the position of the spinning wheel frame may be adjusted as desired, which may be important if the traction rope should stretch or the connections to the rope be not accurately positioned.

The supports C, D, of the spinning wheel frame are vertically in line with the traction rope E, and the guiding and support of the traction rope around the end turns or elsewhere in the spinning run is provided by the inclined sheaves F on which the traction rope runs, these inclined sheaves F being separated below the traction rope sufficiently to permit the arms 13 and the supports C, D to pass between them.

In Figure 3, there is shown a construction in which two spinning wheels A, A' are mounted on opposite sides of the frame G by stud 16 projecting on opposite sides of the frame, this frame G being of any suitable rigid construction and this frame G is suspended from the traction rope E by the same side and center supports C, D, links 11 and slotted connection 12 as in Figures 1 and 2.

It will be seen that the spinning wheel frame and spinning wheel or wheels thereon are free to swing sidewise and move vertically so as to accommodate themselves to any bending of the traction rope E and readily pass such side obstacles as otherwise might slow up the spinning speed. The inclined guide sheaves, also, enable the spinning frame

to be swung vertically in line with the traction rope while assuring the suitable guiding and support of the traction rope, thus securing a more direct and efficient pull of the traction rope upon the spinning frame and wheel. An increased spinning speed and greater certainty of operation is thus secured. The provision for two spinning wheels, also, is important where especially high spinning capacity is desired. 70 75

It will be understood that the invention is not limited to either of the specific constructions shown, but that the form and arrangement of the parts may be varied and many modifications made within the invention 80 claimed. 85

What is claimed is:

1. A cable spinning device having a spinning wheel, a spinning frame carrying said wheel, and frame supporting devices for attachment to a traction rope constructed to permit sidewise swinging of the spinning frame on the traction rope while driven thereby. 90

2. A cable spinning device having a spinning wheel, a spinning frame carrying said wheel, and frame supporting devices for attachment to a traction rope to permit sidewise swinging of the spinning frame on the traction rope while driven thereby and a connection between the spinning frame and supporting devices permitting the vertical movement of the frame on said supporting devices. 95

3. A cable spinning device having a spinning wheel, a spinning frame carrying said wheel, and frame supporting devices for attachment to a traction rope extending downward vertically and in line with the traction rope attachment, said supporting devices being constructed to permit the sidewise swinging of the spinning frame on the traction rope while driven thereby. 100 105

4. A cable spinning device having a spinning wheel, a spinning frame carrying said wheel, and frame supporting devices for attachment to a traction rope extending downward vertically and in line with the traction rope attachment, said supporting devices being constructed to permit the sidewise swinging of the spinning frame on the traction rope while driven thereby and to permit the vertical movement of the frame on the supporting devices. 110 115

5. In a cable spinning apparatus, the combination with the traction rope, of a spinning wheel, a spinning frame carrying said wheel, frame supporting devices mounted on the traction rope and extending downward vertically in line with the traction rope, and traction rope guide sheaves on opposite sides of the traction rope and frame supporting devices, said guide sheaves being separated and inclined from the traction rope to provide space for the supporting devices. 120 125

6. In a cable spinning apparatus, the com- 130

- bination with the traction rope, of a spinning wheel, a spinning frame carrying said wheel, frame supporting devices mounted on the traction rope and extending downward vertically in line with the traction rope, and traction rope guide sheaves on opposite sides of the traction rope and frame supporting devices, said guide sheaves being separated and inclined from the traction rope to provide space for the supporting devices, said supporting devices being constructed to permit the sidewise swinging of the spinning frame on the traction rope while driven thereby.

7. In a cable spinning apparatus, the combination with the traction rope, of a spinning wheel, a spinning frame carrying said wheel, frame supporting devices mounted on the traction rope and extending downward vertically in line with the traction rope, and traction rope guide sheaves on opposite sides of the traction rope and frame supporting devices, said guide sheaves being separated and inclined from the traction rope to provide space for the supporting devices, said supporting devices being constructed to permit the sidewise swinging of the spinning frame on the traction rope while driven thereby and to permit the vertical movement of the frame on the supporting devices.

8. A cable spinning device having a spinning frame, frame supporting devices for attachment to a traction rope extending downward in line with the traction rope attachment, and a plurality of spinning wheels carried by the frame and mounted on opposite sides of the plane of the frame supporting devices.

9. A cable spinning device having a spinning frame, frame supporting devices for attachment to a traction rope, said frame and supporting devices extending downward in line with the traction rope attachment, and a plurality of spinning wheels mounted on opposite sides of the frame.

10. A cable spinning device having a spinning wheel, a spinning frame carrying said wheel, and frame supporting devices including supports C, links 11 between said supports and the frame, intermediate support D having a vertical pin and slot connection with the frame, and connections for mounting the supports on a traction rope to permit swinging of the supports and frame on the rope.

11. A cable spinning device having a spinning wheel, a spinning frame carrying said wheel, and frame supporting devices including supports C, links 11 between said supports and the frame, intermediate support D having a vertical pin and slot connection with the frame, and arms 13 on the supports carrying split sleeves for loosely mounting the supports on a carrier rope.

12. A cable spinning device having a spinning wheel, a spinning frame carrying said

wheel, and frame supporting devices including supports C, links 11 between said supports and the frame and adjustable longitudinally of the frame and support, intermediate support D having a vertical pin and slot connection with the frame, and connections for mounting the supports on a traction rope to permit swinging of the supports and frame on the rope.

In testimony whereof, I have hereunto set my hand.

CHARLES C. SUNDERLAND.
